SUPPORT FOR THE FEET

Filed April 16, 1928

Inventor:
Elisabeth Frei
By B. Singer, Atty.

UNITED STATES PATENT OFFICE

ELISABETH FREI, OF ZURICH, SWITZERLAND

SUPPORT FOR THE FEET

Application filed April 16, 1928, Serial No. 270,558, and in Germany August 22, 1927.

This invention relates to that class of supports for the foot adapted to be inserted in the form of a sole and designed for compensating or rectifying irregularities or deformities of the feet.

A device constructed according to the invention comprises two soles which are only connected together at certain places,—an upper and a lower sole of any desired material,—which are so connected together that a free peripheral portion is provided, at least as to part, so that shaped or "former" pieces of any desired kind can be inserted between the two soles and held fast between them by clamping. One of the soles may be made with advantage of semi rigid or rigid material, for instance from wood, properly cleaned and impregnated to protect it against perspiration, metal, vulcanized fibre or like artificial material to give the foot a firm and elastic hold. The second sole may on the other hand be of relatively soft leather. Moreover between the soles special pockets may be provided for the reception of interchangeable shaped or "former" pieces, for instance those intended for supporting the metatarsal bones of the arch of the foot and the heel.

A number of constructional embodiments of devices constructed according to the invention are shown in the accompanying drawings, in which:—

Fig. 1 is a plan;

Fig. 2 is a side elevation;

Fig. 3 is a transverse section on the line A—B, Fig. 1;

Fig. 4 is a top plan of a second constructional embodiment of the improved foot support;

Figs. 5 and 6 are examples of "former" pieces intended for correcting the foot.

Referring to Figs. 1 to 3, 1 is an upper sole, which is inclined upwards at 3, in order snugly to fit the arch of the foot. This upper sole is connected to a lower sole 2 by means of rivets 4a, 4b, 4c, spaced apart in such a way that the whole peripheral edge between the soles 1 and 2 is freely accessible and so that fixed or interchangeable "former" pieces of leather, rubber, fibre, artificial material,

metal or the like can be inserted. These "former" pieces may extend over approximately the whole length and breadth of the sole or only over a portion thereof, but are held fast in any position by means of the rivets and also by the clamping action between the soles.

The soles 1 and 2 are constituted from different materials. Advantageously, the lower sole 2 is formed from rigid material as for instance from vulcanized fibre, from hardened raw leather, from so called transparent oxhide and the like, and the upper sole is made from softer leather. The soles may also be impregnated to prevent the injurious action of perspiration or to lessen its effect. For heavy people the lower sole 2 may be provided with a metal stiffener.

In the drawings, at Figs. 1, 3, 5 and 6, various former pieces are illustrated. The former piece 5 has a fork shaped cut away portion and is held fast at the rivet 4c. It extends nearly over the whole surface of the sole. 6 is an intermediate former piece for supporting the arch of the foot; and at the side are shown by way of example former pieces 7 and 9 which are designed to prevent the downward slipping of the foot, and which again are attached by corresponding fork shaped slots to the rear rivet. Again on the opposite side of the sole a longitudinally extending former piece may be provided, denoted by 8, which engages the forward rivet 4b by means of a fork shaped slot. The former pieces overlap one another, so that a continuous support for the sole of the foot is obtained and one in which the shape of the support corresponds exactly to the shape of the foot.

Pockets are provided between the soles 1 and 2, which serve for the reception of former pieces. The pockets for the reception of the metatarsal inserted elements 15 are open at both sides. In addition a middle opening 16 is provided, so that the inserted elements can be easily brought to the right position. The pockets for the reception of the inserted pieces for supporting the middle joints of a foot are advantageously made to extend right through; moreover they are di-

vided by means of an intermediate wall 14, so that a plurality of inserted pieces 12, 13 can be placed one above the other each in its own pocket.

- 5 As will be seen from Fig. 4 the soles 1 and 2 instead of being connected together by rivets may be connected in various positions by means of stitching, as at 10a, 10b and 10c. Here again inserted or former pieces are 10 provided, which are denoted in the drawings by 12 and 13, as regards the supporting means for the middle arch portion of the foot. 11 indicates a former body, which engages by means of a fork shaped slot around 15 the stitching 10c and extends along the inner edge of the sole.

Moreover at the outer side of the upper and lower soles 1 and 2, which are connected together by means of the stitching 10a, 10b, 20 10c, side flaps 17 and 17' may be provided, which prevent the slipping down of the foot from the sole with certainty.

The raw leather, transparent oxhide or the like may be hardened by chemical processes and impregnated so that their hardness is not lost through the action of perspiration and water.

In all the constructional forms of the device, the lower sole should be made somewhat 25 shorter than the upper one.

What I claim and desire to secure by Letters Patent of the United States of America is:—

An arch support comprising an upper sole 30 and a lower sole, means by which said soles are attached to each other at different spaced points only so that said soles have a free peripheral edge between the points of attachment, said soles corresponding in length, breadth and contour with the sole of the foot, and pads adapted to be inserted between said soles from the free edge thereof for supporting the longitudinal arch, for supporting the heel and for supporting the metatarsals, and another pad also inserted between said soles and extending approximately over the entire length thereof, said pads being adapted to be secured in position 45 by engagement with the said spaced connecting means, the last named pad bridging the gaps between the metatarsal pads and the arch pads.

In witness whereof I affix my signature.
ELISABETH FREI.
